UNITED STATES PATENT OFFICE

WILLIAM C. FORK, OF HOMEWOOD, ILLINOIS, ASSIGNOR TO ACME STEEL COMPANY, OF CHICAGO, ILLINOIS, A CORPORATION OF ILLINOIS

WINDING REEL FOR METAL STRIPS

Application filed January 4, 1929. Serial No. 330,370.

This invention relates to improvements in winding reels adapted for use in steel mills and the like for winding elongated metal strips into the form of spiral coils. The principal object of the invention is to provide a winding reel adapted to grip automatically the forward end of an advancing strip of hot metal and wind it into the form of a spiral coil without retarding the progress of the strip. A further object is to provide a winding reel comprising improved means for automatically engaging the end of the metal strip which is preferably wound while in a hot condition. A further object of the invention is to provide an improved winding reel embodying means for ejecting the coil of metal from the reel after it has been wound. Still another object is to provide improved means for guiding and controlling the movement of the metal strip as it is fed onto the winding reel. A further object is to provide an improved arrangement of fluid operated means for effecting and controlling the operation of the winding reel and associated mechanism. Other objects relate to various features of construction and arrangement which will appear more fully hereinafter.

The nature and objects of the invention will be understood from the following specification taken with the accompanying drawings in which one embodiment is illustrated.

In the drawings, Figure 1 shows a top plan view of a winding reel embodying the features of the present invention;

Fig. 2 shows a side elevation of the apparatus illustrated in Fig. 1;

Fig. 3 shows an enlarged top plan view of the winding reel proper and associated driving and guiding mechanism;

Fig. 4 shows a transverse section taken on the line 4—4 of Fig. 3;

Fig. 5 is a longitudinal section through the winding reel, similar to the view shown in Fig. 4, but illustrating the ejecting plate or disk in its outer position;

Fig. 6 is a longitudinal vertical section taken on the line 6—6 of Fig. 5 showing the engagement of the metal strip with the teeth of the winding reel;

Fig. 7 is a side elevation of the movable

roller for guiding the strip to the winding reel, showing an associated fluid operated valve in section;

Fig. 8 is an enlarged section taken on the line 8—8 of Fig. 3, showing a side elevation of the parts leading to the winding reel;

Fig. 9 shows an enlarged side elevation and sectional view taken on the line 9—9 of Fig. 3, illustrating in section a valve for controlling the operation of certain fingers by which the progress of the metal strip to the winding reel is controlled;

Fig. 10 is a vertical sectional view taken on the line 10—10 of Fig. 6;

Fig. 11 shows a sectional view taken on the line 11—11 of Fig. 6 in the plane of the advancing sheet of metal; and

Fig. 12 is a somewhat diagrammatic plan and sectional view of the principal parts of the apparatus showing the connections of the fluid operated means by which the guiding of the metal to the reel, the ejection of the metal coil from the reel and the stopping of the coil after it is ejected, are controlled.

In the operation of strip mills in the steel industry, the hot metal slabs are taken from the furnace and are passed endwise through sets of roughing rolls and finishing rolls with the result that an elongated hot metal strip is produced which is fed endwise at relatively high speed by the action of the rolls

and, in some cases, by the action of feeding rolls which may be employed in conjunction therewith. These elongated metal strips may vary in width and thickness according to the requirements to be met by the product of a particular series of operations and, for convenience in subsequent handling, it is desirable that these elongated strips be coiled in spiral fashion while they are still hot.

Since the hot metal strips emerge from the finishing rolls of the mill at a relatively high speed and follow each other in relatively quick succession, it is important that these strips be wound quickly without any retardation of the progress of the metal and without danger of failure or accident in the winding of any particular metal strip, since that would arrest the continuous operation of the strip mill as well as of the winding ap-

95

100

paratus. The present invention provides means whereby successive elongated strips of metal are automatically engaged and wound in spiral form as they are received from the finishing rolls of the strip mill.

As illustrated in the accompanying drawings, the winding machine comprises a cylindrical reel 15 made up of a plurality of teeth 16 having the form shown particularly in Fig. 6, the teeth being arranged at an angle to the axis of the reel and each tooth comprising a forwardly directed flat face 16^a, a rear inwardly divergent face 16^b, and an inner face 16^c extending inwardly from the inner boundary of the face 16^b. There are thus formed between adjacent teeth 16 a plurality of openings 17 so that as the reel rotates in the direction indicated by the arrow 18, one of the openings is adapted to receive the forward advancing end of the hot metal strip 20. This end of the strip is doubled upon itself as shown at 21 by the action of the rotating reel so that the hot metal strip which first engages the reel in the position shown by dotted lines in Fig. 6, subsequently passes around the circular row of teeth 16 and is thereafter wound upon itself in spiral convolutions until the entire strip is wound in spiral form. When the metal strip 20 has been completely wound on the reel 15, it is automatically ejected therefrom by means of an ejecting plate or disk 22 of circular form which is provided with a plurality of openings 23 adapted to permit the teeth 16 of the winding reel to pass therethrough, as shown in Figs. 4 and 6. The reel 15 is so constructed that the teeth 16 project laterally from a circular head 24 through the openings 23 in the ejecting disk 22 and when it is desired to eject a spiral coil from the reel, the disk 22 is moved endwise from the position shown in Fig. 4 to the position shown in Fig. 5, thereby sliding the spiral coil off of the teeth of the reel. The hub of the head 24 of the reel is mounted on a hollow shaft 25 which is mounted to rotate in the bushing 26 secured in the bearing 27 formed on the base 28. A gear 29 is secured on the shaft 25 on the side of the bearing 27 of the reel and this gear meshes with a driving pinion 30 secured on the shaft 32 of an electric motor 33, as illustrated in Fig. 1. The circuit of the electric motor is adapted to be regulated from a control station where the principal operator of the winding machine is located so that the reel 15 may be started and stopped when desired.

The ejecting disk 22 is secured by means of a cap screw 34 on the reduced extremity 35^a of a shaft or piston rod 35 which is mounted within the hollow shaft 25 and spaced therefrom at its forward end by the bushing 36. At its inner or rear end, the shaft 35 is spaced from the surrounding shaft 25 by the combination bushing and coupling member 37

which is secured to the end of the shaft 35 by a transverse pin 38. The coupling member 37 is engaged by a piston rod 39 having an enlarged head 39^a located within the coupling member adjacent to the end of the shaft 35 so that the reciprocating movements of the piston rod 39 are imparted to the shaft or piston rod 35 without any lost motion within the coupling. The piston rod 39 extends into a cylinder 40 and has a piston 41 secured to the end thereof, a stuffing box 42 being located around the piston rod 39 in the end wall of the cylinder. The pipes 43 and 44 lead into opposite ends of the cylinder 40 from a source of compressed air or other fluid pressure supply and, upon admitting the compressed air to the cylinder 40 at the desired end thereof, according to the method hereinafter explained, the piston 41 may be caused to move in the proper direction to effect the desired movement of the ejecting disk 22. As shown in Fig. 4, the cylinder 40 is secured to the side of the base 28 which carries the bearing 27 for the shaft 25.

The elongated metal strip 20 is fed to the winding reel 15 over a feed table 45 comprising the supporting plates 46 and 47 which are mounted on longitudinal frame members 48. This feed table 45 normally has an inclined position as shown in Fig. 2 and the lower end thereof is provided with a bracket 49 mounted to swing about a pivot 50 carried by the brackets 51 which are mounted on the upper sides of the longitudinal frame members 52. The upper surface of the supporting plates 46 preferably is serrated as shown at 46^a in order to give added strength to the member and to allow for unusual expansion due to its direct engagement with the elongated metal strips which move over the surface preferably at a red heat. The elongated metal strips are fed in succession to the feed table 45 from the feed rolls or the like of the finishing mill, not illustrated, and they move upwardly over the table 45 between a guide plate 53 and a guide plate 54 which, when a metal strip of relatively narrow width is being wound, converge upwardly and forwardly as shown in Fig. 1. The upper portion 47^a of the feed table 45 has a plane upper surface upon which are mounted guide blocks 55 mounted for lateral adjustment on the plate 47 by means of pins 56 having heads 56^a which are adapted to slide in the undercut guideway 57 formed in the table. These guide blocks 55 are connected by a screw threaded adjusting member 58 which threadedly engages a boss 59 formed on one guide member and has an interlocking rotative connection with a similar boss 60 formed on the other guide member. By the rotation of this member 58, the guide blocks 55 at the forward side of the machine may be adjusted with respect to the other guide blocks for the purpose of varying their spaced relation and

also for the purpose of varying the spaced relation of the guide plate 54 with respect to the guide plate 53. The guide plate 53 has its inner guiding face in alignment with the 5 stationary guide block 55 and the guide plate 54 has its upper end pivotally connected to the movable guide block 55 as shown at 61 so that the operation of the adjusting member 58 serves also to vary the position of the 10 upper end of the guide plate 54. The lower end of the guide plate 54 is attached to the table 45 by means of a stud 62 which passes through a slot 63 in the flange of the guide plate 54 into a threaded aperture in the table. 15 As the elongated metal strip 20 is fed upwardly over the inclined table 45, the forward end thereof is directed downwardly, near the upper end of the table, by means of an inclined plate 65 which is provided at its 20 lower end with a pair of integral hooks 66 adapted to engage the adjusting member 58. The forward and upper end of the deflecting plate 65 is supported by another pair of integral hooks 67 which extend over a bar 68 25 adapted to rest loosely on the upper edges of the guide plates 53 and 54. The plate 65 thus converges rearwardly toward the inclined feed table 45 and deflects the end of the moving strip 20 downwardly so that it 30 passes beneath a guide roller 70 mounted on a shaft 71 which has bearings 72 carried at the side of the portion 47 of the table. After passing beneath the roller 70, the strip 20 moves along as indicated by dotted lines in 35 Fig. 6 and engages between two of the teeth 16 which are formed on the winding reel 15. In order to effect this interlocking engagement satisfactorily, the strip 20 should preferably engage the teeth 16 some distance below the plane passing through the horizontal 40 axis of the reel. The extent of this downward displacement may vary with the number of teeth in the reel and the thickness of the metal strip being wound and in order that the elevation of the table 45 may be 45 varied to suit the prevailing conditions, the upper end of the table is provided with brackets 73 having sleeves 74 suspended therefrom and internally threaded to be engaged by the adjusting screws 75. As shown particularly in Fig. 10, these adjusting screws are oppositely threaded with the lower threaded portions engaging the internally threaded socket members 76 which are 50 pivoted at 77 on the frame members 52. A hand wheel 78 is secured on one of these adjusting screws and the two screws are connected by a sprocket chain 79 mounted on the sprocket wheels 79^a so that upon rotation of the wheel 78, both of the adjusting screws are 55 simultaneously rotated to effect a uniform elevation or depression of the upper end of the table 45. The strip 20 may thus be caused to engage the teeth of the winding reel 60 at the desired angle and at the desired dis- tance below the center of the reel. With a reel having an external diameter of 18 inches, for example, and 30 teeth distributed uniformly around its periphery, it has been 65 found that the end of the metal strip is engaged and gripped satisfactorily if the table 45 be so disposed as to cause the strip to engage the reel at a distance of about 4 inches from its horizontal plane passing through the 70 axis of the reel. The faces 16^a of the teeth should preferably have an inclination such that they are tangential to a circle having a diameter equal to approximately 45 per cent. of the outer diameter of the reel and the faces 16^b should be tangential to a circle having a 75 diameter approximately 80 per cent. of the outer diameter of the reel, in order to obtain the best results.

As the metal strip 20 moves from the upper end of the table 45 to the reel 15, it is supported and guided on its under side by means of a guide member 80 having a plurality of parallel spaced fingers 80^a which, when the guide member is in its lower position as shown in Fig. 6, are adapted to lie between the 80 spaced guide flanges 81 which are mounted upon the upper end of an inclined discharge table 82. The member 80 is mounted on a transverse shaft 83 journaled in bearings 84 carried by the under side of the upper end 85 of the feed table 45 and during the time when the metal strip 20 is passing into its initial engagement with the winding reel 15, the guide member 80 occupies the position shown in Fig. 8 wherein the upper surfaces of the 90 guide fingers 80^a lie flush with the upper surface of the portion 47 of the feed table. The guide member 80 is adapted to be held in the position shown in Fig. 8 through a crank arm 85 which is fixed on the shaft 83 95 and which is connected through a link 86 with an arm 87 secured to the end of a piston rod 88. This piston rod has its opposite end secured to a piston 89 which is mounted to 100 travel in a compressed air cylinder 90 secured to the under side of one of the frame members 48, as shown in Fig. 6. A pipe 91 leads into this cylinder at the end thereof opposite that through which the piston rod 88 emerges, and when compressed air or other 105 compressed fluid is admitted through this pipe 91, the piston 89 is forced toward the left, as viewed in Fig. 6, thereby compressing the coil spring 92 and moving the crank arm 85 into the position shown in Fig. 6, wherein the 110 guide fingers 80^a are depressed into the spaces between the guide flanges 81. When the fluid pressure within the cylinder 90 is released, the spring 92 forces the piston 89 toward the right, as viewed in Fig. 6, thereby 115 moving the guide fingers 80^a into their normal upper position in alignment with the upper surface of the table 47. The fingers 80^a retain this normal position during the 120 time that the metal strip 20 is passing into its 125

initial engagement with the teeth 16 of the winding reel and they are then depressed by the admission of compressed fluid to the cylinder 90, as hereinafter explained, to remain in that depressed position until after the wound coil has been ejected from the winding reel by the movement of the ejecting disk 22 to the position shown in Fig. 5.

As soon as the forward end of the moving strip 20 is interlocked with the teeth of the rotating reel 15, it is carried around in the direction indicated by the arrow 18 in Fig. 6 and the portion of the oncoming strip of metal in proximity to the reel then assumes the inclined position shown at 20^a in Fig. 6 with the upper surface of the lower portion of this inclined section of the strip contacting with the lower peripheral surface of the guide roller 70 while the intermediate portion of the inclined part 20^a is engaged by the floating guide roller 95 mounted on a shaft 96 which is journaled in the roller frame 97. The floating guide roller 95 normally occupies the lower position shown in Fig. 8, before the metal strip 20 reaches the reel 15, but the passing of the metal strip around the reel elevates the roller 95 to the position shown in Fig. 6 as permitted by the movement of the roller frame 97 with the shaft 71 on which the roller 70 is mounted, the frame 97 having arms 97^a which are fixed on the shaft 71 between the roller 70 and the bearings 72. The innermost end of the shaft 71 has an arm 98 secured thereon and this arm carries an adjustably mounted counterweight 99 adapted to counterbalance the weight of the roller frame 97 and parts carried thereby so that the guide roller 95 will not unduly depress the hot metal strip 20 as it passes through the inclined pathway indicated at 20^a. The inner end of the shaft 96 extends beyond its bearing in the frame 97 and has an auxiliary guide roller 95^a mounted thereon so that this guide roller may be brought into close proximity to the ejecting disk 22 when the machine is being used for winding relatively narrow strips which would pass to the winding reel adjacent to the disk 22 when that disk is in its retracted position.

When the roller frame 97 and the roller 95 are in the lowermost position shown in Fig. 8, or in the intermediate position shown in Fig. 6, for example, these parts would interfere with the action of the disk 22 in ejecting a wound roll or coil from the winding reel 15 and means are therefore provided for moving the frame 97 and roller 95 to the position shown by dotted lines at 100 in Fig. 8. For this purpose, the shaft 71 on which the arms 97^a of the frame 97 are secured, is provided at its inner end with a relatively fixed hub member 101 within which is mounted a crank arm 102 adapted to pivot about the shaft 71 and to engage the flange 101^a

of the hub member 101 when the latter is in the position shown in Fig. 8. The lower end of the crank arm 102 is pivotally connected with a link 103 which has its opposite ends pivotally attached at 104 to the forward end of a piston rod 105. This connection is established through a head 106 on the piston rod which is adapted to travel on a guide flange 107. The piston rod 105 extends through the end wall of a cylinder 108 and is secured to the piston 109 adapted to travel therein. The piston 109 is normally forced toward the right, as viewed in Fig. 8, by a coil spring 110 and it is moved in the opposite direction by the action of compressed fluid which is admitted through a pipe 111. When compressed fluid is admitted through the pipe 111, as hereinafter described, the crank arm 102 forces the frame 97 upwardly to the position shown by dotted lines at 100, through the engagement of the arm 102 with the hub member 101, thereby permitting the ejecting disk 22 to be actuated to remove a wound coil of metal from the winding reel 15. When the piston 109 is in the normal position shown in Fig. 8, it holds the crank arm 102 in the lower position, thus permitting the frame 97 to drop to the lowermost position shown in Fig. 8 or to be elevated by the action of the moving strip of metal as shown in Fig. 6.

The roll of metal which is ejected from the winding reel 15 by the action of the disk 22 drops onto the discharge table 82 which occupies the inclined position shown in Figure 2, being supported at its upper end by a transverse I-beam 115 resting on the longitudinal frame member 52. The lower end of the discharge table 82 is supported by the transverse block 116. The wound roll of metal rolls by gravity down this inclined table 82 between parallel upwardly extending guide plates 117, 117^a and 118 which have their lower edges secured to the upper surface of the table. At the lower end of the table 82, the progress of the roll is adapted to be arrested by a movable table section 120 which is adapted to be moved upwardly to form a gate for arresting the progress of the roll. The section 120 is pivotally mounted on a shaft 121 having bearings in brackets 122 which are fixed on the frame member 52 and it normally occupies an inclined position wherein its upper surface forms a continuation of the upper surface of the table 82 and also of the lower inclined table 123 carried by the frame member 52. The shaft 121 has a crank arm 124 fixed thereon and this arm is pivotally connected through a link 125 with a piston rod 126 arranged to extend into a fluid pressure cylinder 127 where it is secured to a piston 128 as shown particularly in Fig. 12. A coil spring 129 normally forces the piston 128 toward the left as viewed in Figs. 2 and 12 so that the inclined table section 120 is normally

maintained in its lower position wherein it forms a continuation of the table 82; but when compressed air or other fluid is admitted to the cylinder 127 through a pipe 130, the piston 128 is forced toward the right as viewed in Figs. 2 and 12, thereby moving the table section 120 into its upper inclined position so that it stops the progress of the roll of metal and holds it in the position indicated at 131 in Fig. 2, thereby permitting an operator to pass a section of wire through the roll of metal strip and fasten this wire around the free end of the metal strip to prevent the unwinding thereof, during its further handling. After the free end of the wound strip has been bound with a piece of wire in this manner, the operator releases the compressed fluid from the cylinder 127, thereby permitting the table section 120 to return to its lower inclined position by the action of the coil spring 129, so that the roll 131 is then permitted to continue by gravity over the table section 120 and downwardly over the table 123 where it passes between the upwardly extending guide plates 132. The guide plates 117^a, 118 and 132 have extensions which project over the lateral edges of the table section 120, as shown at 133, thus guiding the roll 131 as it passes over the section 120. The wound rolls of metal are commonly passed from the lower end of the table 123 onto a suitable carriage or rack in which a number of rolls or strips may be collected preliminary to be engaged by a large hook 35 for movement therefrom by the action of a crane or other transfer mechanism.

The connections of the fluid pressure system for controlling the operation of the winding machine are shown somewhat diagrammatically in Fig. 12 and the operation of these parts may best be understood in connection with a summary of the operation of the entire apparatus. Assuming that the machine is being employed for winding an elongated strip of hot metal proceeding from a strip mill and fed to the winding machine by the action of the rolls on the metal, this hot metal strip travels up the inclined feed table 45, the elevation of which has been regulated 45 by the adjustment of the screws 75 in order to cause the strip 20 to engage the winding reel 15 at the desired distance below the axis of the reel. As the strip passes over the table 45, it is guided on its lateral side by the guide plates 53 and 54 which have been regulated in their spaced relation, through the operation of a screw 58, to suit the width of the metal strip being wound, and the strip then passes between the guide roller 70 and beneath the floating guide roller 95, or 95^a where it is supported on its under side by the movable guide fingers 80^a. These guide fingers 80^a, carried by the member 80 are normally held in a position where they form a continuation of the upper portion 47 of the

guide table by the action of the coil spring 92 in the cylinder 90, shown particularly in Fig. 6, whereby the piston 89 is forced toward the right so that the link 86 pushes the crank arm 85 in a counter-clockwise direction 70 to elevate the member 80. As soon as the strip 20 interlocks with the teeth of the winding reel 15 and is carried around the circumference of the reel by the rotation thereof, the floating guide roller 95 (or 95^a) is elevated by the action of the metal strip assuming the inclined position shown at 20^a in Fig. 6, and, as soon as this occurs air is admitted to the cylinder 90 to cause the guide fingers 80^a to be depressed below the peripheral surface of the ejection disk 22. This operation is effected automatically by the tilting of the roller carrying frame 97 which is fixed on the shaft 71, the rotation of this shaft by the upward tilting of the frame 97 75 serving to operate certain devices illustrated particularly in Fig. 12. The compressed fluid is received from a source of supply through a pipe 140 which has a branch pipe 140^a leading into a four-way valve 141 from 80 which air may be exhausted through the port 142. The supply pipe 140 for compressed air or the like has a branch pipe 143 which leads into the casing of a valve 144 having a valve member 144^a which is normally retained on 85 its seat by a coil spring 144^b. From the upper chamber of this valve, a pipe 145 connects with the previously described pipe 91 which leads into the head end of the cylinder 90. An exhaust pipe 146 leads from the pipe 100 91 through an exhaust valve 147 having a valve member 147^a which is normally retained on its seat by a coil spring 147^b. The valve member 147^a has a stem 147^c through which it may be depressed to open the valve 105 147^a and permit air to exhaust from the cylinder 90. When the guide rollers 95 and 95^a are in their lowermost positions, as shown in Fig. 8, the valve stem 147^c is depressed by the action of a valve operating arm 148 which is 110 secured on the shaft 71 thereby permitting air to escape from the cylinder 90 and preventing the piston 89 from moving toward the left, as viewed in Figs. 6 and 12, by the action of compressed fluid. However, as 115 soon as the shaft 71 is turned by the upward movement of the roller carrying frame 97, due to the lifting of the rollers 95 or 95^a by the metal strip 20, the valve operating arm 148 is turned upwardly from the position 120 shown in Fig. 12, thereby permitting the valve 147^a to close. At the same time, the valve stem 144^c of the valve 144^a is depressed by the action of a valve operating lever 149 which is pivoted at 150 on a bracket 125 151, as shown in Fig. 8. The valve operating lever 149 is actuated by a cam 152 which is secured on the shaft 71 so that as the shaft is turned by the elevation of the roller carrying frame 97, the lever 149 is actuated to 130

open the valve 144 and permit compressed air to pass from the pipe 143 through pipe 145 to the cylinder 90, thereby moving the piston 89 toward the left, as viewed in Fig. 5 12, to depress the guide fingers 80^a. The guide member 80 and the guide roller 95 then retain the position shown in Fig. 6 during the winding of the metal strip until the strip has been entirely wound into the form of a 10 spiral coil, whereupon the roller frame 97, being no longer supported by the metal strip, is free to drop to the position shown in Fig. 8 which would operate to open the exhaust valve 147 through the action of the arm 148 and thereby permit the fingers 80 to be 15 elevated by the action of the coil spring 92 in the cylinder 90, since the valve 144^a would then be allowed to close under the action of the coil spring 144^b, but this action does not 20 take place, or if it does occur, it is immediately reversed by the action of the attendant, who, upon observing that the winding of the elongated metal strip has been completed, actuates the four-way valve 141 to 25 cause compressed air or other fluid to pass through a pipe 154 to a branch pipe 155 and thence through a pipe 156 in the direction indicated by the arrow 157, it being permitted to flow in that direction only through 30 the pipe 156 by the action of a check valve 158. From the pipe 156 the air is admitted through the previously-described pipe 111 into the cylinder 108 thereby causing the piston 109 to move toward the right, as 35 viewed in Fig. 12 with the result that the crank arm 102 is operated to turn the member 101 and thereby elevate the roller frame 97 and the rollers 95 and 95^a to positions wherein they do not interfere with the action 40 of the disk 22 in ejecting wound coils from the cylinder 40. When the piston 109 reaches the limit of its movement corresponding to the position of the roller frame 97 indicated by dotted lines at 100 in Fig. 8, the ejecting disk 45 22 is actuated from the cylinder 40 through the operation of an arm 159 which is carried by the head 106 previously described as being carried at the end of the piston rod 105. This arm 159 actuates the valve stem 160^a 50 connected to a valve member 160^b located in a valve casing 160. The valve member 160^b is normally closed by a coil spring 160^c but when the plunger 160^a is engaged by the member 159, the valve is opened to permit 55 compressed air to pass from the pipe 156 through the valve casing and thence through a pipe 161 which communicates with the pipe 43 leading to the cylinder 40 so that the piston 41 is then forced toward the left as viewed 60 in Fig. 4 to cause the disk 22 to eject the wound coil from the reel 15. During this operation the air in the cylinder 40 on the forward side of the piston 41 is permitted to exhaust through the pipe 44 which leads to 75 the four-way valve 141 and which has the

exhaust port 142. When the wound coil has been ejected from the reel 15, the four-way valve 141 is turned to cause compressed air to flow through the pipe 44 to the cylinder 40, thereby moving the piston 41 toward the right as viewed in Fig. 4 to retract the ejecting disk 22. During this reverse operation of the piston 41, the air is exhausted from the rear end of the cylinder 40 through the pipe 43 and thence through the pipe 154, it being permitted to flow in that direction as indicated by the arrow 163 because of the provision of a check valve 164 in the pipe 154 to allow compressed fluid to flow in that direction only. When the disk 22 has been thus withdrawn, the operator actuates a foot release valve 165 which is located adjacent the four-way valve 141 in an exhaust pipe 166 which leads from the pipe 111 connected to the cylinder 108. Upon opening the valve 165 to permit the air in the cylinder 108 to escape to the atmosphere, the piston 109 is forced toward the left, as viewed in Fig. 12, by the action of the coil spring 110, thereby allowing the roller 95 to return to the position shown in Fig. 8.

The supply pipe 140 through which the compressed air or the like is received at the machine, has an extension 140^b which is connected with a valve casing 170 in which is mounted a valve member 171 normally retained on its seat by a coil spring 172. This valve member is adapted to be opened against the compression of the spring 172 by a manually operated lever 173. A pipe 174 leads from the casing 170 to the cylinder 127, previously described, containing the piston 128 by which the operation of the table section 120 is controlled. Since the valve member 171 is normally retained on its seat by the coil spring 172, air is normally allowed to pass from the pipe 140^b through the pipe 130 to the cylinder 127 thereby forcing the piston 128 toward the right as viewed in Fig. 12 to elevate the table section 120. When a wound coil has been ejected from the reel 15 and allowed to roll down against the table section 120, the operator presses on the lever 173 to allow the air to escape from the valve chamber 170 and from the cylinder 127, the lowest portion 171^a of the valve member then engaging its seat to prevent further flow from the pipe 140^b. The coil spring 129 then moves the piston 128 toward the left as viewed in Fig. 12 to depress the table section 120 and allow the wound coil of metal to continue to roll by gravity over the discharge table 123. In this way, successive wound coils of metal strip are momentarily arrested by the member 120 to permit wires to be tied around the outer ends of the wound strip, and then these wound coils are permitted to roll down the table 123 to be received by the truck or other device on which 13

they are stored or by which they are handled.

Although one form of the invention has been shown and described by way of illustration, it will be understood that it may be constructed in various other embodiments within the scope of the appended claims.

I claim:

1. The combination in a winding machine for a moving metal strip, of a reel comprising a plurality of teeth adapted to engage the forward end of said strip, the rear face of each tooth extended intersecting the front face of the next succeeding tooth intermediate its end edges to define a guiding mouth for receiving the advancing edge of said strip, means for revolving said reel, and a plate of larger diameter than said reel having apertures fitted by said teeth and movable along said teeth for ejecting the wound coil from said reel.

2. The combination in a winding machine for a moving metal strip, of a reel comprising a plurality of relatively stationary teeth adapted to engage the forward end of said strip, the rear face of each tooth extended intersecting the front face of the next succeeding tooth intermediate its end edges to define a guiding mouth for receiving the advancing edge of said strip, said metal strip moving toward said reel in a plane displaced from the axis of said reel, and means for rotating said reel.

3. The combination in a winding machine for a moving metal strip, of a rotatable reel comprising a plurality of relatively fixed teeth adapted to engage the forward end of said strip, each of said teeth comprising a flat front face and a pair of complementary rear faces converging therefrom, and means for rotating said reel.

4. The combination in a winding machine for a moving metal strip, of a reel comprising a disk having a plurality of teeth projecting laterally therefrom, each of said teeth having its front face inclined to the radii of said disk and a rear face adapted when extended inwardly to intersect the front face of the next following tooth between the front and rear edges thereof, said teeth being relatively fixed on said disk, and means for rotating said disk.

5. The combination in a winding machine for metal strips, of a rotatable reel having means for engaging the forward end of a metal strip, a feed table over which the metal strip passes to said reel, a movable guide member adapted to form a continuation of said feed table, an ejecting disk of larger diameter than said reel adapted to move longitudinally of the axis of said reel for ejecting a wound coil of metal therefrom, and means for actuating said movable guide member to move it out of the path of said ejecting disk.

6. The combination in a winding machine

for metal strips, of a rotatable reel having a plurality of teeth adapted to engage the forward end of a moving strip of metal, a feed table over which said metal strip moves, a movable guide member adapted normally to form a continuation of said feed table adjacent said reel, a movable guide roller adapted to engage the upper side of said metal strip adjacent said reel and to be moved upwardly by said strip after engagement of said strip with said reel, and means for rotating said reel.

7. The combination in a winding machine for metal strips, of a rotatable reel having a plurality of teeth adapted to engage the forward end of a moving strip of metal, a feed table over which said metal strip moves, a movable guide member adapted normally to form a continuation of said feed table adjacent said reel, a movable guide roller adapted to engage the upper side of said metal strip adjacent said reel and to be moved upwardly by said strip after engagement of said strip with said reel, and means actuated by the upward movement of said guide roller for causing a movement of said movable guide member out of guiding position.

8. The combination in a winding machine for metal strips, of a rotatable reel having a plurality of teeth adapted to engage the forward end of a moving strip of metal, a feed table over which said metal strip moves, a movable guide member adapted normally to form a continuation of said feed table adjacent said reel, a movable guide roller adapted to engage the upper side of said metal strip adjacent said reel and to be moved upwardly by said strip after engagement of said strip with said reel, an ejecting member of

larger diameter than said reel for effecting movement of a wound coil of metal therefrom, means for moving said ejecting member longitudinally of said reel, and means for moving said guide roller and said movable guide member out of the path of said ejecting member.

9. The combination in a winding machine for metal strips, of a rotatable reel having a plurality of teeth adapted to engage the forward end of a moving strip of metal, a feed table over which said metal strip moves, a movable guide member adapted normally to form a continuation of said feed table adjacent said reel, a movable guide roller adapted to engage the upper side of said metal strip adjacent said reel and to be moved upwardly by said strip after engagement of said strip with said reel, an ejecting member of larger diameter than said reel for effecting movement of a wound coil of metal therefrom, means for moving said ejecting member longitudinally of said reel, and fluid-operated means under the control of the operator for effecting upward movement of said guide roller out of the path of said ejecting member.

ber, and means actuated by the upward movement of said guide roller for effecting movement of said movable guide member out of the path of said ejecting member.

5 10. The combination in a winding machine for metal strips, of a reel having a plurality of teeth adapted to engage the forward end of a moving strip of metal, means for rotating said reel, a feed table over which said metal strip moves to said reel, a guiding frame pivotally mounted adjacent said reel, a roller mounted on said frame for engagement with the upper side of said metal strip adjacent said reel and manually controlled means for effecting movement of said guiding frame to effect corresponding movement of said roller away from said strip.

10 15. The combination in a winding machine for metal strips, of a reel having a plurality of teeth adapted to engage the forward end of a moving strip of metal, means for rotating said reel, a feed table over which said metal strip moves to said reel, a guiding frame pivotally mounted adjacent said reel, a roller mounted on said frame for engagement with the upper side of said metal strip adjacent said reel and manually controlled means for effecting movement of said guiding frame to effect corresponding movement of said roller away from said strip, and a second guide roller mounted on a stationary axis adjacent said movable guiding frame.

15 20. The combination in a winding machine for metal strips, of a rotatable reel having a plurality of teeth adapted to engage the forward end of a moving strip of metal, means for rotating said reel, a feed table over which said metal strip moves toward said reel, a movable guide member adapted normally to form a continuation of said feed table adjacent said reel, a movable guide roller adapted to engage the upper side of said metal strip adjacent said reel, means for moving said movable guide member out of guiding position, and means actuated by the movement of said roller for controlling said last-named means.

20 25. The combination in a winding machine for metal strips, of a rotatable reel having means for engaging the forward end of a metal strip, a feed table over which the metal strip passes to said reel, a movable guide member adapted to form a continuation of said feed table and movable out of operative position, and fluid actuated means for operating said movable guide member.

25 30. The combination in a winding machine for metal strips, of a rotatable reel having means for engaging the forward end of a metal strip, a feed table over which the metal strip passes to said reel, means for actuating said reel to cause the peripheral portion thereof to move upwardly adjacent the end of said feed table, a frame pivotally supported at one edge adjacent the end of said feed table,

and a roller mounted at the other edge of said frame to ride upon said metal strip as it is being wound upon said reel.

30 35. The combination in a winding machine for a moving metal strip, of a rotatable reel having means to engage the forward end of said strip, a feed table for guiding said metal strip to said reel, a pair of relatively adjustable side plates on said feed table for accommodating metal strips of different width, and a detachable inclined guide plate above said feed table beneath which said metal strip is adapted to pass.

35 40. In testimony whereof, I have subscribed my name.

40 WILLIAM C. FORK.
